W. BAUSCH ET AL

LENS BLANK HOLDING MEANS

Filed June 29, 1926

UNITED STATES PATENT OFFICE.

WILLIAM BAUSCH AND JOHN R. POWELL, OF ROCHESTER, NEW YORK, ASSIGNEES TO BAUSCH & LOMB OPTICAL COMPANY, OF ROCHESTER, NEW YORK, A CORPORATION OF NEW YORK.

LENS-BLANK-HOLDING MEANS.

Application filed June 29, 1926. Serial No. 119,445.

The present invention relates to lens blank holding means and has for one object the provision of improved lens holding means for use in the production of fused bifocal lenses.

5 A further object is to provide improved means for holding a minor lens blank or segment in tilted position upon a major lens blank to permit the former to gradually and progressively approach and unite with the 10 latter during the fusing period whereby to avoid the inclusion of air bubbles between the fused parts.

15 A further object of the invention is to provide improved holding means for lens blanks which is of simple construction, comparatively cheap to manufacture and convenient to operate, and which is capable of withstanding the high temperatures to which it is subjected in the fusing of the blanks supported thereby.

20 To these and other ends the invention resides in certain improvements and combinations of parts, all as will be hereinafter more fully described, the novel features being pointed out in the claims at the end of the 25 specification.

In the drawings:

Figure 1 is a plan view illustrating one embodiment of the invention;

Figure 2 is a front elevation of the same;

30 Figure 3 is a side elevation;

Figure 4 is a rear elevation;

35 Figure 5 is an enlarged sectional elevation showing the parts in position for holding the minor lens blank or segment in tilted position upon the major lens blank;

40 Figure 6 is a similar view showing the position assumed by the tilted lens blank, or segment after fusion of the latter with the major lens blank; and

45 Figure 7 is a sectional elevation taken on line 7^a—7^a of Figure 1.

Similar reference numerals throughout the several views indicate the same parts.

50 In the fusing of bifocal lens blanks of the variety, for example, in which the major blank is recessed to receive the button or segment constituting the reading portion of the lens, it is essential that the latter be held in tilted position within the recess of the former when placed in the furnace to permit it to gradually and progressively unite with the main or distance blank, so that all air bubbles which may form between the blanks will be driven out during the fusing process.

Referring to the drawings, 10 represents generally, a base comprising a frame 11 and a holder or support 12 thereon for the major lens blank 13 which is recessed at 14 to receive the minor lens blank or segment 15, as shown in Figure 5. The support 12 may be formed of any suitable material capable of withstanding the fusing temperatures to which the lens blanks are subjected. The frame 11 is preferably formed of a suitable metal which will also resist the relatively high temperatures to which the parts are subjected during the fusing process. The upper face of the support 12 is shaped to conform to the face of the lens blank to be disposed thereon. A space 16 is provided between the support 17 and the frame, the latter having an opening 17 for admitting heated air to circulate directly in contact with the bottom of the support 12.

The frame 11 is provided with a pair of upstanding front lugs 18 and also a pair of upstanding rear lugs 19 which serve to center and hold the support 12 in proper position within the frame. The lugs 19 are extended above the support 12 and are curved on their inner faces to receive and prevent rearward displacement of the lens blank 13. Extended upwardly from the base and preferably from the lugs 19 are a pair of pins or supports 20 suitably connected with said lugs 19 and forming parts upon which to adjustably mount the means for holding the blank or segment 15 in the tilted position shown in Figure 5.

The tilting means proper comprises a bar 21 having openings 22 adjacent its opposite ends for receiving the pins 20, the openings being slightly larger in diameter than the pins to permit the bar to have a limited swinging movement about an axis passing through the pins. The bar is provided with a centrally disposed and laterally projecting arm 22 extended above the segment or blank 15 in spaced relation thereto. The arm carries on its free end a weight 23 constituting also a handle for lifting the bar and which may be formed integral with or connected to the arm in any desired manner. The arm is preferably inclined upwardly as shown and together with the weight 23 serves to tilt or rock the bar 21 upon the pins 20 a slight amount to cause it to bind thereon, which is permitted by reason of the fact that the holes 22 are

slightly greater in diameter than the pins 20. The bar is provided with suitable depending means for engagement with the outer edge of the blank or segment 15 whereby it is held in the tilted position upon the blank 13 as shown in Figure 5. The depending blank engaging means preferably comprises a pair of spaced fingers 24 or equivalent means arranged to rest on the lens blank 15 to hold it in the desired tilted position upon the edge of the major lens blank 13, and against rocking in a direction transverse to the direction of tilting. The lower ends of the fingers 24 are made to engage the blank 15 rearwardly of the centers of the pins 20. By thus positioning the fingers any pressure exerted upwardly thereon, due to expansion of the segment 15 when being heated in the furnace, will tend to rock or increase the tilt of the bar from the normal inclined position in which it is held by the weighted arm, thus increasing the binding action between the ends of the bar and the supporting pins therefor and hence locking it against upward displacement.

As the temperature to which the glass is subjected is increased to the point at which the latter begins to soften, the action of gravity will cause the segment 15 to gradually descend to the bottom of the recess 14, the downward swinging movement of the segment resulting in the lower surface thereof being made to progressively contact with the surface of the major lens 13, thus forcing out any air bubbles tending to form between the blanks while the latter are being fused or united one with another.

We claim as our invention:

1. A device for holding a lens segment in tilted position upon a lens blank, comprising a base for supporting the blank, spaced guides extending upwardly from the base, a bar slidable and tiltable upon the guides and adapted to be frictionally held in adjusted position thereby, said bar having downwardly projecting means adapted to engage the segment rearwardly of said guides to hold it in said tilted position and serving also to prevent its rocking in a direction transverse to the direction of tilting, and a weight connected with said bar and serving to hold it tilted in the desired position of adjustment.

2. A device for holding a lens segment in tilted position upon a lens blank comprising a base for supporting the blank, spaced supports extending upwardly from the base, a member tiltable upon the supports to be frictionally held thereby and including a weighted portion overlying the segment in spaced relation thereto, and spaced fingers projecting downwardly from said member and engaging the segment to hold it in said

tilted position and serving also to prevent its rocking in a direction transverse to the direction of tilting.

3. A device for holding a lens segment in tilted position upon a lens blank, comprising a base for supporting the blank, a member tiltably mounted upon the base about an axis at one side thereof and downwardly projecting spaced fingers carried by said member adapted to engage the segment rearwardly of said axis, said fingers serving to hold the segment in tilted position and preventing its rocking in a direction transverse to the direction of tilting.

4. A device for holding a lens segment in tilted position upon a lens blank, comprising a base for supporting the blank, spaced pins extending upwardly from the base, a bar tiltably positioned upon said pins whereby it is frictionally held thereon, depending means carried by the bar adapted to engage the segment to hold it in said tilted position and also serving to prevent it from rocking in a direction transverse to the direction of tilting, and a weight for holding said bar in tilted position comprising an arm projecting from the bar and having an upstanding portion forming a handle for adjusting the bar upon said pins.

5. A device for holding a lens segment in tilted position upon a lens blank comprising a base for supporting the blank, spaced pins extending upwardly from the base, a bar having openings slightly larger than the pins adapted to receive the latter, spaced fingers depending from said bar adapted to engage the segment rearwardly of the pins to hold it in tilted position, an arm extending laterally from the bar and forwardly of said fingers in spaced relation to the segment and an upstanding weight upon the arm forming a handle for adjusting the bar and causing the latter to tilt upon the pins whereby it is frictionally held in adjusted position thereon.

6. A device for holding a lens segment in tilted position upon a lens blank, comprising a base for supporting the blank, a bar having a limited swinging movement upon the base about an axis at one side thereof and having downwardly extending means adapted to engage the segment rearwardly of said axis to hold it tilted upon the blank and to prevent its rocking in a direction transverse to the direction of tilting and a forwardly projecting weight extending from the bar over the segment in spaced relation thereto and serving to hold the bar in position to maintain said downwardly extending means in engagement with the segment.
